UNITED STATES PATENT OFFICE.

ROBERT KROEDEL, OF ROCHESTER, NEW YORK, ASSIGNOR TO EASTMAN KODAK COMPANY, OF ROCHESTER, NEW YORK, A CORPORATION OF NEW YORK.

ROLL-FILM-DEVELOPING APPARATUS.

1,266,491.

Specification of Letters Patent. Patented May 14, 1918.

Application filed November 22, 1917. Serial No. 203,305.

To all whom it may concern:

Be it known that I, ROBERT KROEDEL, of Rochester, in the county of Monroe and State of New York, have invented certain new and useful Improvements in Roll-Film-Developing Apparatus; and I do hereby declare the following to be a full, clear, and exact description of the same, reference being had to the accompanying drawings, 10 forming a part of this specification, and to the reference-numerals marked thereon.

My present invention relates to photography and more particularly to apparatus for the daylight development of roll film and the invention has for its object to provide a simple, light and convenient device suitable for use by amateurs that will quickly and safely spread the film for exposure to the developing fluid. To these and 15 other ends the invention resides in certain improvements and combinations of parts all as will be hereinafter more fully described, the novel features being pointed out in the claims at the end of the specification.

25 In the drawings:

Figure 1 is a perspective view of a film developing apparatus constructed in accordance with and illustrating one embodiment 30 of my invention;

Fig. 2 is a similar view of the tank portion alone;

Fig. 3 is a perspective view of the cover detached and inverted;

35 Fig. 4 is a longitudinal sectional view through the assembled device showing the initial positions during its operation, intermediate portions of the cover and tank being broken away;

40 Fig. 5 is a longitudinal section, also broken away at an intermediate point, showing the final positions of the parts, and

Fig. 6 is a transverse section taken substantially on the line 6—6 of Fig. 5.

45 Similar reference numerals throughout the several views indicate the same parts.

The apparatus of my invention is particularly adapted for the development of the smaller sizes of film cartridges which 50 are so narrow as to be held flat without difficulty and which are not of great length. The device comprises generally an elongated tank 1 and a sliding cover 2 therefor which slides longitudinally of the tank and covers 55 the top thereof. The tank is of a length

approximating that of the film strip for the development of which it is intended and its width is also approximately that of the strip, the tank being preferably rectangular. Its upper side edges are flanged outwardly at 3 to be embraced by inwardly turned flanges 4 in the cover that form light-tight slots or runways. One end of the tank has a rolled edge 5 and beneath it impaling spurs 6 on the exterior of the end wall. The adjacent end of the cover is provided with an apron and hand hold 7 that overhangs these devices and conceals and protects them. On the inside of the tank at the same end is a transverse bar 8 elevated 65 slightly from the bottom of the tank.

The inner or advance end of the cover 2 is provided with a depending roll holding box 9 having four side walls but open at its bottom which opening is presented toward the bottom of the tank in slightly spaced relation thereto.

In use, the leader 10 at the outer or free end of the film roll 11 is unwound slightly and impaled upon the spurs 6 as shown in 80 Fig. 4. It is drawn over the rolled edge 5 of the tank after having been passed beneath the bar 8, the roll itself resting in the tank adjacent to the bar. The cover is now applied in such manner that the box 9 fits 85 over the roll but not so tightly but what the latter will be free to turn, as shown in Fig.

4. The cover is then engaged with the flanges 3 and shoved into closed position. The advancing end traverses the length of 90 the tank and carries the roll with it through the medium of the box 9 so that the film is unrolled and spread, sensitive side up, upon the bottom of the tank as shown in Fig. 5. The developing agent can be poured into 95 the tank at any time, preferably at the point in the process illustrated in Fig. 4 after the cover has been applied but not closed. After the film is spread the tank may be rocked to

flow the developer back and forth as usual. 100 The emulsion side of the film being uppermost at all points, there is no opportunity for bubbles to collect.

After the development is completed, I prefer to remove the film (Fig. 5) by disengaging the lead end 10 from the prongs 6 and pinching this end against the end of the cover while withdrawing the latter from the closed position to a position corresponding to that of Fig. 4. This draws the film 110

strip from the container coincidently with the act of opening the same and in the open position, the cover may be lifted off to release the spool.

- 5 At any time during the treatment of the film the baths ordinarily used, that is, developer, water and fixing agent may be interchanged and poured in and out by slightly withdrawing the cover from the position of Fig. 5, the adjacent wall of the roll holding box 9 acting as a light guard. For instance, between the developing and fixing treatments, water may be introduced to wash out the developing solution.
- 10 15 The flanges 3 on the tank terminate short of the end thereof at which the impaling devices are located so that the cover may be brought down over the film roll as in Fig. 4 and then engaged with the flanges.
- 20 I claim as my invention:

1. In a film developing apparatus, the combination with an elongated tank, of a

cover for the latter having a sliding engagement longitudinally of the tank and means on the cover for unrolling a film roll contained in the tank as the cover is closed. 25

2. In a film developing apparatus, the combination with an elongated tank, of a cover having a sliding engagement with the tank longitudinally thereof and a roll film 30 holder carried beneath the advance end of the cover.

3. In a film developing apparatus, the combination with an elongated tank, of a cover having a sliding engagement with the tank longitudinally thereof, a roll holding box carried beneath the advance end of the cover and means on an end wall of the tank for fastening the free end of a film roll contained within the box. 35

ROBERT KROEDEL.
